UNITED STATES PATENT OFFICE.

OTTO POLANEK, OF CHICAGO, ILLINOIS.

BLANK LABEL FOR BOOK COVERS AND METHOD OF APPLYING SAME.

Application filed November 1, 1920. Serial No. 420,991.

To all whom it may concern:

Be it known that I, OTTO POLANEK, a citizen of the United States, and a resident of the city of Chicago, in the county of Cook and State of Illinois, have invented certain new and useful Improvements in Blank Labels for Book Covers and Methods of Applying Same, of which the following is a full, clear, and exact specification.

10 This invention relates to improvements in blank labels for book covers and method for applying same and particularly for the covers of memorandum books, with a view to subsequently exteriorly indicating on the 15 label therefor the name of the owner or its number, title, etc., as may be desired.

The object of my invention is to provide the cover of a book with a blank label, the exposed surface of which is depressed below 20 the outer surface of the cover for a book and which consists of a material upon which may be subsequently written with a pen or pencil or printed, the name of the owner or the number of the book or other identification 25 thereof, and whereby said label is isolated from frictional wear and defacement to which the surrounding surface of the book is exposed, and especially when carried in the pocket of its user or owner.

30 A further object of my invention is to provide a cover of books with a blank label adapted to receive and retain marks identifying the ownership or contents of the book, the material of which necessitates the employment of both heat and pressure for its 35 application thereto.

Another object of my invention is to provide the cover of a book with a blank label depressed below the exposed surface of the 40 cover and adapted to be subsequently written or printed upon, the securing of which label in its operative position requires the simultaneous mechanical application of both heat and pressure.

45 With these ends in view, my invention finds embodiment in certain features of novelty in the construction, combination and arrangement of parts by which the said objects are attained, all as hereinafter fully 50 described with reference to the accompanying drawings and more particularly pointed out in the claims.

In said drawings,—

Fig. 1 is a perspective view of the cover of 55 a book in which my invention finds its embodiment.

Fig. 2 is a transverse section taken through the cover for a book, on the line 2—2 of Fig. 1, and also illustrating respectively in front elevation and cross-section the transverse sheet following the removal of the material of the label therefrom.

For the illustration of my invention I have selected the cover for an ordinary pocket blank book or diary, the outer surface 60 of which commonly consists of a comparatively thin woven fabric, artificial leather, and sometimes real leather folded upon itself at 3 to form the opposite sides 4—4 of the cover, which fabric or leather is stiffened throughout except across its fold, by a lining 5 of paper board which is preferably somewhat soft or spongy for purposes hereinafter described.

For applying the label 6 to the cover so 75 constructed, the sheet of enameled paper 7 is laid with its enameled surface resting upon the cover or a sufficient portion thereof to conform to the predetermined size of the label to be applied to the cover, and thus 80 arranged they are then projected between the fixed and a movable die of an ordinary die press and with the enameled sheet opposed to the surface of the movable die.

The surfaces of both dies are smooth and 85 plain, with the contour of the movable die conforming to that of the label to be applied, the movable die being in a heated condition and, as may be, the fixed die.

The cover and the enameled sheet thus ar- 90 ranged are then projected between the two dies and while resting upon an ordinary fixed die (not shown) are subjected to the heat and pressure of the usual movable die 9, the compressive force of which is sufficient to 95 force a substantial portion of the enamel from the paper, as indicated at 8, into the fibers of the cover, depressing the cover beneath the deposited enamel below the plane 100 of the surface of the cover and the exposed surface of the enamel, to so harden and smooth the exposed surface of the enamel that characters for indicating the ownership, number or other identification of the 105 contents of the cover may be conveniently and clearly written or printed upon the surface of the label so formed.

The use of a blank label consisting of enamel deposited from enameled paper, concurrently compressed and depressed into the 110 surface of a cover with the exposed surface of a label in a plane below that of the sur-

rounding surface of the cover, is an important feature of my invention, resulting, as it does, in isolating the surface of the label and thereby preventing the printing thereon 5 from being defaced by frictional wear to which the other portions of the cover are exposed in handling, packing in numbers for shipment, and particularly when carried in the pocket of the user of the memorandum 10 sheets or other sheets contained between the leaves of the cover.

At this point it is to be observed that by the employment of a yielding or spongellike paper board as a lining for the cover, the 15 depression for the label may be made in the cover without showing on the exposed surface of the lining.

The color of the enameled paper is preferably white, but it may be tinted to suit 20 the fancy, and in practice I have found from various tests and experience that ordinary enameled paper commonly on the market may be used, and this whether it is enameled 25 upon either one or both of its surfaces; but in practice I preferably use what is commonly designated and known to the trade as paper "foil" to but one surface of a sheet of which the enamel is applied and which is made by a secret process, which I do not 30 know and which has not yet been disclosed to the trade.

For the purposes of my invention, there is, however, this difference,—that the use of foil paper requires that the fabric of the 35 cover be sized at the point of location of the label and with a sizing the character of which is such that it is fused by heat; whereas, with the use of enameled paper made by any of the processes of common knowledge, 40 no sizing of the cover is necessary, and if used results in the sticking of the fibers of the paper from which the enamel is deposited for the label and which cannot be removed without defacing the label itself.

45 In conclusion, it is to be observed that my invention includes the use of any number of blank labels of any desired form or arrangement for deposit books for banks and

upon which may be subsequently written in ink, pencil, or printed by the bank, its title, 50 the name of the depositor, and such other data of identification as the bank or its customer may desire, and that these labels may be affixed to the cover as herein described, either separately or simultaneously with one 55 operation.

Having described my invention, what I claim and desire to secure by Letters Patent is:

1. A book cover the exposed surface of 60 which is provided with a yielding material, and a label therefor the substance of which is directly united with said material and depressed in a plane below the surrounding surface of the cover. 65

2. A book cover the exposed surface of which is provided with a yielding fibrous material, and a label therefor depressed in a plane below the surrounding surface of the cover, the substance of which label directly contacts with and is united with said fibers. 70

3. A fabric book cover, provided with a blank label consisting of dry enamel directly contacting with said fabric and depressed 75 inwardly therein in a plane below the surrounding fabric of the cover.

4. The herein described method for applying blank labels to book covers, consisting in first applying to the fabric of the 80 cover a sizing melting under heat, overlaying the sized portion of the fabric with a loose sheet of enameled paper, and then subjecting said fabric and loose sheet to heat and pressure operating to transfer the enamel from the paper to the fabric to form a depression in the surface thereof surrounding the transferred enamel and temporarily melt the sizing in the presence of the deposited enamel. 85

90 In witness whereof, I have hereunto set my hand and affixed my seal, this 27th day of October, A. D. 1920.

OTTO POLANEK. [L. S.]

Witness:

JNO. G. ELLIOTT.
